United States Patent

Des. 241,705

Patented Oct. 5, 1976

241,705

IMPACT WRENCH

Eimatsu Kotone, No. 4-44, 5-chome, Nogami,
Takarazuka, Hyogo-ken, Japan

Filed July 3, 1975, Ser. No. 593,044

Term of patent 14 years

Int. Cl. D8—05

U.S. Cl. D8—68

FIG.1

FIG.2

FIG.3

FIG.4

FIG.5

FIG.6

FIG.7

FIG. 1 is a perspective view of an impact wrench, showing the new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a side elevational view taken from the left of FIG. 2; and

FIG. 7 is a side elevational view taken from the right of FIG. 2.

I claim:

The ornamental design for an impact wrench, as shown.
